ABSTRACT

A safety circuit which is provided with two separate amplification channels, each of which comprises two cascade-connected amplifiers. An approval signal is applied to a common input, and an approval signal can be derived from a common output if the units to be supervised function properly.

SAFETY CIRCUIT FOR THE DETECTION OF THE SIMULTANEOUS ACTUATION OF TWO ANTAGONIZING UNITS

The invention relates to a safety circuit for the detection of the simultaneous actuation of two antagonizing units, each of which is supplied with an alternating voltage via a static switch, the said circuit supplying an approval signal if no supply voltage is simultaneously applied to the two antagonizing units.

Antagonizing units are to be understood to mean herein units which for reasons of safety may never be simultaneously active. For example, these units may be the green traffic lights which control the access of vehicles to two intersecting roads, in which case the simultaneous lighting up of the two lights constitutes a major danger. For controlling traffic lights, use is increasingly made of static power switches of the Triac type which are controlled by signals originating from a control logic.

In spite of all precautions taken in the choice and the use of the switches and of the components of the control logic, certainty cannot be obtained that no internal faults will occur in the control logic or in the switches (due to short-circuit or interruption of one or two junctions of a Triac). These faults might cause the simultaneous lighting up of the green lights, the lighting up of a light being complete or partial, depending on whether it is caused by one half-cycle or by both half-cycles of the alternating voltage.

The safety circuit has for its object to detect dangerous situations of this kind and to supply an approval signal if no voltage is simultaneously applied to the two lights, and to suppress this signal in the opposite case. However, this circuit must be designed such that, no matter what faults occur in its connections and/or components, the approval signal is definitely suppressed if the status of the switches gives rise to a dangerous situation.

The invention has for its object to provide a new structure for a safety circuit of this kind for use when the antagonizing lights (and more in general two antagonizing units) are supplied via static switches.

According to the invention, a safety circuit of this kind comprises two amplification channels which receive an approval signal of a given frequency, the outputs thereof being coupled to the output of the safety circuit, each amplification channel comprising a cascade-connection of two amplifiers, the direct current supply for these two amplification channels being provided for one of the amplification channels by a pair of supply circuits which are each connected to the terminals of the switch which controls one of the antagonizing units, and for the other amplification channel by another pair of supply circuits, each of which is connected to the terminals of the switch which controls the other unit, both supply circuits of each pair comprising a rectifier which is arranged in one supply circuit so as to rectify the positive half-cycles of the alternating voltage and in the other supply circuit so as to rectify the negative half-cycles, these two supply circuits supplying the one and the other amplifier of the amplification channel, respectively.

The invention will be described in detail hereinafter with reference to the figures.

FIG. 1 shows the diagram of a safety circuit according to the invention.

FIG. 2 is a table showing the various states of the traffic lights and the switches.

In FIG. 1 the safety circuit is used for the detection of the simultaneous lighting up of two antagonizing green traffic lights at an intersection. These two lights L_1 and L_2 are supplied by the alternating voltage between the supply lines 1 and 2 via the switches S_1 , S_2 (Triacs). The terminals 3, 4 of the switches S_1 , S_2 are connected to line 1 via the lights L_1 and L_2 . The terminals 5 and 6 are connected to line 2. In this example, the switches are Triacs, which means a switch which is made of semiconductor material in which pn-junctions are provided, the said switch being active for both positive and negative voltages and being controllable at a control terminal. The switches S_1 , S_2 have control terminals 7, 8 which are connected to the logic unit 9 which controls the traffic lights.

In the case of normal operation, logic unit 9 never supplies signals which cause the simultaneous lighting up of the two lights L_1 and L_2 . However, the latter situation may arise if given faults occur in the logic unit. Faults can also occur in the switches S_1 , S_2 . These faults (short-circuit or interruption) can occur in the one as well as in the other pn-junction or in both junctions at the same time. In the case of faults in the logic unit or in the switch, both lights L_1 and L_2 can light up simultaneously, a light being supplied by the positive half-cycles or the negative half-cycles of the alternating voltage or by both. In any case, the simultaneous lighting up of the two lights L_1 and L_2 is considered dangerous.

The safety circuit detects all combinations of states of the switches S_1 and S_2 which give rise to a dangerous situation. Between its two output terminals 10 and 11 the safety circuit supplies an approval signal for the status combinations which do not give rise to a dangerous situation, and it suppresses this signal for a dangerous situation.

The table of FIG. 2 illustrates all status combinations of the switches S_1 and S_2 .

In the first column the possible status combinations are numbered from 1 to 16. The second and the third column relate to switch S_1 . Column A_1^+ relates to the pn-junction which can be conducting during the positive half cycles of the alternating voltage, and the column A_1^- relates to the pn-junction which can be conducting during the negative half-cycles. The symbols 1 and 0 in these columns indicate that the relevant pn-junction is conducting or non-conducting, respectively. The fourth and the fifth column A_2^+ and A_2^- indicate in the same manner for the switch S_2 the states of the pn-junctions which can be conducting during the positive and the negative half-cycles, respectively. The columns L_1 and L_2 show the states of the lights L_1 , L_2 . The symbol 0 indicates that no voltage is applied to a light (extinguishing). The symbol 1 indicates that a voltage is applied to a light (lighting up). No distinction is made between a voltage comprising positive and negative half-cycles and a voltage having only positive or only negative half-cycles. In the last column S the symbol 1 denotes a non-dangerous status combination for which the safety circuit must supply an approval signal, and the symbol 0 denotes a dangerous status combination for which the safety circuit must suppress the approval signal.

As is shown in the table of FIG. 2, the safety circuit must supply an approval signal (S = 1) for the status

combinations 1, 2, . . . 7 in which at least one of the two switches S_1 and S_2 is non-conducting for the positive and/or the negative half-cycles of the alternating voltage. The approval signal must be suppressed ($S=0$) for the status combinations 8, 9, . . . , 16 in which both switches are conducting.

According to the invention, the safety circuit shown in FIG. 1 comprises two amplification channels 12, 13, the input of which receives an approval signal of a given frequency, the said signal always being present between the terminals 14, 15. The outputs of the two amplification channels 12, 13 are coupled to the output terminals 10, 11 of the safety circuit via the transformer 16. The latter comprises two primary windings 17 and 18 which are connected to the output of the amplification channels 12 and 13, respectively, and a secondary winding 19 which is connected to the terminals 10, 11. Each amplification channel 12, 13 comprises two amplifiers 20 and 21, 22 and 23, respectively, which are cascade-connected and which are coupled via a transformer 24, 25. The direct current supply for the amplification channel 12 is provided by the supply circuits 26, 27, the inputs of which are connected parallel to the terminals 3, 5 of the switch S_1 (directly for the terminal 3, and by way of the resistor 28, 29 for the terminal 5). The direct current supply for the amplification channel 13 is provided by the supply circuits 30, 31, the inputs of which are connected parallel to the terminals 4, 6 of the switch S_2 (directly for the terminal 4, and by way of the resistor 28, 29, for the terminal 6). Each of the supply circuits 26, 27 comprises a rectifier 32, 33, respectively. The rectifier 32 of the circuit 26 is connected so as to rectify the positive half-cycles of the alternating voltage, and the rectifier 33 of the circuit 27 is connected so as to rectify the negative half-cycles. Each of the supply circuits 30, 31 comprises a rectifier 34, 35, respectively. The rectifier 34 of the circuit 30 is connected so as to rectify the positive half-cycles of the alternating voltage, and the rectifier 35 of the circuit 31 is connected so as to rectify the negative half-cycles. In the supply circuits 26, 27, 30, 31 the rectifiers 32, 33, 34, 35, respectively, are connected to a smoothing circuit which consists of the parallel connection of a Zener diode 36, 37, 38, 39 and a capacitor 40, 41, 42, 43, respectively. The direct voltages which are obtained on the outputs of the supply circuits 26, 27 are applied to the input terminals of the amplifier 20, 21, respectively, of the amplification channel 12. Similarly, the direct voltages obtained on the outputs of the supply circuits 30, 31 are applied to the input terminals of the amplifier 22, 23, respectively, of the amplification channel 13.

In the safety circuit the supply circuits 26, 27, 30 and 31 perform the function of detectors of the status of the switches S_1 and S_2 . The two amplification channels 12 and 13 perform the function of a logic circuit which allows passage of the approval signal or blocks this signal in accordance with the table of FIG. 2.

This is because the supply circuit 26 applies a supply voltage to the amplifier 20 only if an alternating voltage containing positive half-cycles is present on the input, i.e. when switch S_1 is not conducting during the positive half-cycles. The supply circuit 27 applies a supply voltage to the amplifier 21 only when the switch S_1 is not conducting during the negative half-cycles. In the same manner, the supply circuits 30 and 31 apply a supply voltage to the amplifier 22, 23 only if the switch S_2 is

not conducting during the positive or negative half-cycles, respectively, of the alternating voltage.

In the status combinations 1, 2, . . . 7 according to the table of FIG. 2, at least one of the switches S_1 and S_2 is not conducting for the positive and/or negative half-cycles, with the result that the amplifiers of at least one amplification channel 12 or 13 receive their supply voltage. The approval signal which is applied to the input terminals 14, 15 of the safety circuit then reaches the output terminals 10, 11.

In the status combinations 8, 9, . . . 16 of the table of FIG. 2, both switches S_1 and S_2 are conducting during at least one of the two half-cycles of the alternating voltage, with the result that at least one of the amplifiers of the two amplification channels 12 and 13 receives no supply voltage. In this case the two amplification channels 12 and 13 are blocked, with the result that the approval signal is suppressed.

The safety circuit shown in FIG. 1 optimally satisfies the safety rule that faults in the connections or components can cause the suppression of the approval signal, but in any case prevent that the suppression does not take place in one of the dangerous status combinations 8, 9, . . . 16. In general it is assumed that the component faults to be taken into consideration are a short-circuit or an interruption for the pn-junctions and the capacitors, and an interruption for the resistors and windings of the transformers.

The two amplification channels 12, 13 between the input 14, 15 and the output 10, 11 of the safety circuit are constructed in conformity with the said safety rule.

Each of the amplifiers can be constructed as shown in FIG. 1 for amplifier 20. This amplifier comprises a transistor 44, the base of which is connected to the input terminal 15 by way of the resistor 45, its emitter being connected to the input terminal 14 and to the supply terminal $-$, and its collector being connected to the supply terminal $+$ by way of the resistor 46 and the primary winding of the transformer 24. The resistor 45 limits the current at the input of the amplifier 20, with the result that in the case of a fault in this transistor the approval signal is substantially not applied to the amplifier 21. The resistor 46 limits the collector current of the transistor 44. Connected between the terminals of the primary winding of the transformer 24 is the diode 47 in order to eliminate overvoltages which might damage the transistor 44. A fault in one of the components of the amplifier 20 causes suppression of the approval signal in the amplification channel. The approval signal on the output terminals 10, 11 is then immediately suppressed if the light L_2 is on or will be interrupted as soon as the light L_2 is switched on.

The supply circuits 26, 27 and 30, 31 are also constructed in conformity with the said safety rule. In the case of an interruption or a short-circuit of the rectifier 32 of the supply circuit 26 or a short-circuit of the capacitor 40 or of the Zener diode 36, the amplifier 20 is no longer supplied with a voltage and the approval signal is suppressed in the amplification channel 12. In the case of interruption of the Zener diode 36 or of the capacitor 40, the amplifier 20 is not normally supplied and can possibly function, but in that case the supply circuit 26 continues to perform its function as detector of the status of switch S_1 .

The approval signal which is applied to the input of the safety circuit may be a sinusoidal alternating voltage, but can alternatively be a pulse-shaped signal.

For an intersection comprising a plurality of pairs of antagonizing traffic lights, the number of safety circuits equals the number of said pairs. It will then be advantageous from a safety point of view to connect these safety circuits in cascade so as to form one safety unit comprising one input and one output for the approval signal.

What is claimed is:

1. A safety circuit for the detection of the simultaneous actuation of two antagonizing units, each of which is supplied with an alternating voltage via a static switch, said safety circuit supplying an approval signal if no supply voltage is simultaneously applied to the antagonizing units, characterized in that it comprises two amplification channels which receive an approval signal of a given frequency, the outputs thereof being coupled to the output of the safety circuit, each amplification channel comprising a cascade-connection of two amplifiers, the direct current supply for these two amplification channels being provided for one of the am-

plification channels by a pair of supply circuits which are each connected to the terminals of the switch which controls one of the antagonizing units, and for the other amplification channel by another pair of supply circuits, each of which is connected to the terminals of the switch which controls the other antagonizing unit, both supply circuits of each pair comprising a rectifier which is arranged in one supply circuit so as to rectify the positive half-cycles of the alternating voltage and in the other supply circuit so as to rectify the negative half-cycles, these two supply circuits supplying the one and the other amplifier of the amplification channel, respectively.

2. A circuit as claimed in claim 1, characterized in that each amplifier comprises a transistor, the base of which is connected to an input terminal of the amplifier, its emitter being connected to the other input terminal of the amplifier and to a supply circuit output terminal, and its collector being connected to the other supply circuit output terminal by way of a primary winding of a coupling transformer.
